SPONGE ELECTRODE

Filed May 25, 1928

UNITED STATES PATENT OFFICE

FREDERICK H. WAPPLER, OF FLUSHING, AND WILLIAM LOOS, OF JAMAICA, NEW YORK, ASSIGNORS TO WAPPLER ELECTRIC COMPANY, INC., OF LONG ISLAND CITY, NEW YORK, A CORPORATION OF NEW YORK

SPONGE ELECTRODE

Application filed May 25, 1928. Serial No. 280,444.

Our invention relates to sponge electrodes; that is, to electrodes having a flexible pad member of insulating material and made preferably of soft rubber, in connection with a flexible sheet-like member made of conducting material and used as an electrode, for applying electric currents to the human body.

More particularly stated, we seek to produce an electrode of this general type, especially adapted for applying electric currents of various kinds, and including high frequency currents, directly to the human skin without danger of producing burns or blisters, and without causing disagreeable sensations to the patient.

As is well known in this art, the application of electric currents directly to the skin of a patient, so as to produce results entirely satisfactory is a matter of some difficulty.

While heretofore it has been common practice to use electrodes for applying to the skin both direct and interrupted galvanic currents and also faradic currents, and in some instances high frequency oscillating currents, not every electrode has been suitable for these purposes.

Generally speaking, it is a difficult matter to apply an electrode to the human skin so as to obtain anything like constant, uniform or dependable conditions of operation. This is generally true even when the electrode, where in contact with the skin, is moistened, as is usually the case.

Ordinarily when the electrode is made flexible as for instance when it is constructed of wire netting, thin sheet metal or the like, and supported upon a flexible body of insulating material such as rubber or felt, there is difficulty in sterilizing or otherwise cleaning the electrode, without disengaging it from its mounting. And yet for sanitary reasons, it is desirable to remove the electrode from its mounting, in order to clean each of these parts.

By our invention we seek to reduce to a minimum the various drawbacks above mentioned, and to improve the efficiency of the electrode.

Further, we provide our improved elec-

trodes with a metallic bridge, for facilitating the use of the electrode in connection with a belt or other flexible supporting member, to hold the electrode in position while in use.

We also provide our electrode with multiple connectors having the form of eyes and used like binding posts, arranged to reduce to a minimum the number of cord conductors required for connecting the electrode or electrodes in different ways. By giving the connectors the form of spring eyes and making them flat, they are prevented from projecting outwardly to any appreciable extent, so that a patient can lie upon them without discomfort.

Reference is made to the accompanying drawing forming a part of this specification, and in which like reference characters indicate like parts throughout the several figures.

Figure 1 is a side elevation of one form of our improved sponge electrode, and shows one way of connecting it with a conductor through which the currents are supplied.

Figure 2 is a plan view of the mechanism shown in Figure 1.

Figure 3 is a section on the line 3—3 of Figure 1, looking in the direction indicated by the arrows.

Figure 4 is a fragmentary section, showing a portion of the flexible band of conducting material, and an end hook carried thereby.

Figure 5 is a plan showing a different way of connecting the conductor with the flexible conducting band.

Figure 6 is an elevation showing our sponge electrode as held in position by a belt or band for the purpose.

Figure 7 is a fragmentary plan of a portion of the flexible conducting band used for supplying the electric currents.

A pad member of insulating material is shown at 10 and in this instance comprises a body of porous rubber 11, carrying an unbroken skin 12 of soft rubber as its outer surface. This pad member 10 is preferably an ordinary rubber sponge, of a kind commonly used in hospitals, and sold from most

drug stores. Such a rubber sponge is practically water tight, as no water can soak through the outer skin.

Encircling the pad member 10 is a flexible band 13 of conducting material, the structure of which is indicated more particularly in Figure 7. Links 8, made of metal, are held together by metallic rings 9; and thus is formed an articulated fabric, made entirely of metal, and all parts of which are conducting. The material thus used may be of the kind known as silversmith's stock. It is essentially a flexible conducting material, light, thin and strong, and capable 15 of presenting in the aggregate a relatively large surface for fitting against the human skin.

The band 3 is preferably rather wide, as shown, and at its ends is provided with a 20 pair of metallic end strips 14, each extending the entire width of the band and bent to form a hook 15.

A connecting plate 16 is provided with a 25 pair of oppositely disposed reverting edges 17.

The connecting plate 16 is used to span over the distance from one of the hooks 15 to the other. In practice the band 13 is first bent around the pad member 10, the 30 connecting plate 16 is next brought into such position that one of the reverting edges 17 fits into one of the hooks 15, and then the opposite hook 15 is brought into engagement with the other reverting edge 17.

35 In order to remove the band 13, the pad member is squeezed slightly by hand and thus compressed, and one of the hooks 15 is thereupon slipped out of engagement with the adjacent reverting edge 17. This disconnects the band from the pad member 10.

40 Mounted upon the connecting plate 16 is a bridge 18 of metal, and carried by this bridge is a binding post 19, detachably fitted upon a small base 20, as indicated more particularly in Figure 3.

45 A contact pin 21, carried by a cord conductor 22, is detachably fitted into the binding post 19, and is used for connecting the cord with the electrode, and disconnecting the same therefrom.

In some instances it is desirable to connect the conducting cord 22 with one end of the connecting plate 16, as shown more particularly in Figure 5. For this purpose 50 we provide ends of the bridge 18 with eyes 23 so that the contact pin 21 may be readily thrust through these eyes.

By providing two sets of eyes 23, the cord conductor 22 may be connected with either 55 end of the bridge 18, and thus practically with either edge of the band 13 of conducting material.

In some instances we find it desirable to simply press the electrode against the 60 skin of the part to be treated. In other in-

stances the electrode is placed under the arm or under the chin of the patient and thus held in position.

It is sometimes desirable however, to hold the electrode in position by aid of a belt or band, as shown in Figure 6. Here the belt or band is slipped beneath the bridge 18, brought around, and fastened in any appropriate way. In the particular instance illustrated in Figure 6, the electrode is applied to a leg 25 by means of the band or belt 24. Of course, a belt or band around the waist, neck or other part of the patient's body may be used as occasion requires.

We find in practice that the sponge electrode above described can be used in quite a variety of different ways, in such manner as to produce different results.

It is desirable to give the flexible band 13 material a relatively large area as compared with the total area of the rubber sponge or other pad member 10. By this arrangement the available operating surface of the electrode is rendered quite large, and hence it is not necessary to pass so much current through a given area of skin. Thus the tendency to burn or blister the skin, or to produce unpleasant sensations therein, is greatly reduced. Again, by having the operating surface relatively large, the tendency for the currents to dry out the moisture of the skin, or the artificial moisture employed with the electrode, is also greatly reduced, and this is a result looking toward uniformity of action.

The sponge electrode as a whole has a considerable amount of flexibility. This is due to the fact that the rubber sponge is practically always exceedingly flexible and elastic, and the metallic band 13, in consequence of its construction above described and particularly illustrated in Figure 7, is exceedingly flexible.

The net result is that the electrode as a whole may be easily and quickly and yet accurately, brought into conformity with almost any portion of the human body to which the electrode is required to be fitted, in order to insure an equal distribution of current throughout the area to be operated upon.

We do not limit ourselves to the particular mechanism here illustrated and described, as variations may be made therein without departing from our invention, the scope of which is commensurate with our claims.

Having thus described our invention, what we claim as new and desire to secure by Letters Patent is as follows:

1. A device of the character described, comprising a pad member of insulating material, a flexible band of conducting material engaging said pad member and provided with hook-ends, a connecting plate pro-

vided with reverting edges detachably engaging said hook-ends in order to hold said band upon said pad member, and a conductor connected with said connecting plate.

5 2. A device of the character described, comprising a flexible pad member, a flexible band of conducting material engaging said pad member, a connecting plate for engaging the ends of said band in order to hold said band detachably in position upon said pad member, a bridge mounted upon said connecting plate, a flexible member threaded through said bridge in order to hold said pad member against some part of the human 10 body, and means for connecting a conductor with said first mentioned band member.

15 3. In a device of the character described the combination of a pad member, a flexible band of metallic webbing for engaging said pad member, said band having end portions provided with hooks, a connecting plate provided with portions for engaging said hooks in order to hold said metallic webbing upon said pad member, and electrical connections 20 carried by said connecting plates.

25 4. In a device of the character described the combination of a pad member, a flexible band of conducting material engaging said pad member and provided with hooks, a connecting plate provided with portions for engaging said hooks in order to hold said flexible band detachably in position upon said pad member, and electrical connections 30 carried by said connecting plate.

35 5. The combination of a rubber sponge having a body portion of porous rubber covered with an unbroken skin of soft rubber, a flexible band of conducting material mounted upon said unbroken skin of soft 40 rubber, and means for supplying electric currents to said flexible band.

45 6. The combination of a pad member provided with a porous body portion and a skin covering said porous body portion and integral therewith so as to render the same practically water tight, and a flexible band of conducting material encircling said pad member and detachable relatively thereto.

50 7. A sponge electrode comprising a rubber sponge provided with a skin of soft rubber integral with said rubber sponge, and a flexible band of conducting material detachably mounted upon said skin of soft rubber and made up of separate metallic links connected together and directly engaging said 55 skin of soft rubber.

60 8. A device of the character described, comprising a rubber sponge provided with a skin of soft rubber integral therewith, a band of silversmith's stock carried by said rubber sponge and engaging the skin of soft rubber, and means for connecting an electric conductor with said member of silversmith's stock.

65 9. The combination of a pad member, a

flexible band of conducting material engaging said pad member, mechanism connected with the ends of said band and together with said band normally encircling said pad member, and connections for supplying electric current to said band.

70 10. The combination of a pad member of insulating material, a flexible band of conducting material engaging said pad member and provided with end portions, a metallic member detachably connected with said end portions and together with said band normally encircling said pad member for the purpose of detachably holding said flexible member upon said pad member, and 75 electrical connections carried by said metallic member.

80 11. In a device of the character described the combination of a pad member, a flexible band of conducting material separate from said pad member, a connecting plate, means for detachably connecting said connecting plate with the ends of said flexible band in order to hold said flexible band detachably in position upon said pad member 85 by frictional engagement therewith, and electric connections carried by said connecting plate.

90 12. The combination of a pad member of insulating material, a flexible member of conducting material engaging said pad member and serving as an electrode, fastening members carried by said flexible member, a connecting plate made of conducting material and provided with fastening members 95 for detachably engaging said flexible member, so as to hold said band thereupon by frictional engagement, and electrical connections for said connecting plate.
